UNITED STATES PATENT OFFICE

HARRY R. PRIEST, OF LOUDONVILLE, OHIO

DISPENSING RECEPTACLE

Application filed May 15, 1930. Serial No. 452,730.

The object of this invention is to provide a neat and inexpensive device whereby a person may provide a supply of face cream, soap, or other toilet preparations in paste form, and retain the same for personal use when traveling and under all conditions. The invention seeks to provide a device particularly designed for holding commodities in paste-like form and facilitating the withdrawal of a portion of the commodity for use without entailing any waste. The invention is illustrated in the accompanying drawing and will be hereinafter fully set forth.

In the drawing:
15 Figure 1 is a diametrical section of a device embodying the invention,
Fig. 2 is a top plan view of the same,
Fig. 3 is a bottom plan view,
Fig. 4 is a view partly in elevation and
20 partly in section of a modification, and
Fig. 5 is a detail showing a further modification of the base.

In carrying out the invention, there is provided a cylindrical body 1 which is preferably hollow, as shown, to provide a chamber 2 in which a reserve supply of material may be placed. The closed end of the body has external threads, as shown at 3, while its open end is interiorly threaded, as at 4, and has 25 an enlarged bore whereby to produce a shoulder 5 against which a mirror 6 may seat. To retain the mirror in place, a base member 7 is threaded into the open end of the body, the base shown in Fig. 1 being a ring having 30 a flange 8 at its outer end adapted to bear against the end of the body and thereby limit the inward movement of the ring so that it cannot be caused to exert a crushing impact upon the mirror. The flange also imparts 35 an attractive finish to the article and facilitates grasping of the base when its withdrawal is desired. A packing strip, indicated at 9, is provided between the base and the mirror to further guard against breakage. Threaded onto the closed end of the body 1 is a cap member 10 which may be of any desired 40 length and of the same material as the body, the cap being interiorly threaded for its full length so that it may be threaded onto the body and caused to move downwardly on the

same by merely rotating it in an obvious manner. At the center of the closed end of the cap is formed a very small outlet opening 11 through which the paste-like commodity disposed within the cap may be discharged. As 55 shown, the internal threads 12 of the cap extend the full length thereof except for a short distance 13 at the open end of the cap, the smooth bore 13 facilitating the fitting of the cap over the body. The threads on the 60 body, however, extend only a very short distance along the same so that the exposed portion of the body will be smooth and will not detract from its sightliness. The end of the cap is slightly tapered externally, as at 14, 65 to enhance the attractiveness of the finish.

In Fig. 4, the base 15 is closed at its inner end by a web 16 having an axial opening therethrough to receive a screw 17 whereby it may be secured to a wall or other fixed support, this arrangement providing for a supply of soap or the like at a fixed point. In 70 Fig. 5, is shown a base 18 consisting of a solid block which may sometimes be preferred.

Ordinarily, the cap and the body 1 will be 75 filled with the creamy or paste-like preparation which it is intended to dispense and when the cap has been engaged with the end of the body, the commodity within the cap will be all enclosed so that the device may be 80 handled without the user having the commodity ejected onto his hands or person in an objectionable manner. When it is desired to use a portion of the material, the cap is rotated slightly so that it will ride down on 85 the body which thereupon will serve as a plunger or follower to compress the paste-like material and cause a portion of the same to discharge through the opening 11. As the issuing stream of matter will be very 90 small, it, of course, can be easily cut off at any time and waste of the material will be thereby avoided. The device is exceedingly 95 simple and may be constructed of any material so that it may be very light and will not prove a burden when being carried for use. The surface of the device may be ornamented as may be desired and the discharge of the commodity may be very nicely regulated. When the entire contents of the cap 100

have been used, the supply may be immediately replenished by transferring to the cap the reserve supply contained in the body and, when convenience permits, the body may be refilled so that very little attention will be needed to maintain a constant supply of the material ready for use.

It may, sometimes, be deemed desirable to omit the threaded connection between the 10 cap and the body, in which event a slight push on the cap will effect discharge of the commodity, and it is also feasible to have the base extend up around the cap to enclose the same so that the cap will slide into the 15 base when expelling the contained commodity.

Having thus described the invention, I claim:

1. In dispensing receptacles of the class 20 described, a hollow body open at one end, a base member threaded into the open end of the body and provided with a flange extending beyond the wall of said body, and a closure for said open end forming a compartment in the hollow body for a reserve supply of material, said closure being held in said body by the base member, the flange of the base member engaging the edge of the open end of said body and limiting insertion of the member so that the closure is not crushed by the member.

2. In dispensing receptacles of the class 35 described, a hollow body open at one end, a base member threaded onto the open end of the body and provided with a flange extending beyond the wall of said body, and a mirror constituting a closure for the open end of the body and forming a compartment above it in the hollow body for a reserve supply of 40 material, said mirror being held in the hollow body by said base, the flange of said base contacting the end edge of the open end of the body and limiting insertion of said base so that the mirror is not crushed by the base.

45 3. In dispensing receptacles of the class described, a hollow body open at one end, a base threaded onto the open end of the body and provided with a flange extending beyond the wall of said body, a closure for the open 50 end of the body forming a compartment in the hollow body for a reserve supply of material, said closure being held in the hollow body by said base, the flange of the base engaging the end edge of the open end of said body and limiting insertion of the base in the body so that the closure is not crushed by the base, and a screw having the head secured in said base and confronting said closure and having the threaded end projecting 55 beyond said base for permanently attaching said dispensing receptacle to a fixed support.

In testimony whereof I affix my signature:

HARRY R. PRIEST. [L. S.]
